(57) **CLAIM**

The ornamental design for a bottle, as shown and described.

DESCRIPTION

FIG. 1 is a perspective view of a bottle showing the new design;

FIG. 2 is a front elevation view thereof, with the rear elevation, left side elevation, and right side elevations being identical thereto;

FIG. 3 is a top perspective view thereof; and,

FIG. 4 is a bottom perspective view thereof.

The broken lines in the drawings represent portion of the bottle that form no part of the claimed design.
